(57) CLAIM

The ornamental design for a tool with brush, as shown and described.

DESCRIPTION

FIG. 1 is a lower front perspective view of a tool with brush of the present invention;

FIG. 2 is an upper back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an upper back perspective view thereof in an alternate configuration with a tool insert removed; and,

FIG. 10 is a back view thereof showing the fin removal tool engaging a surf board fin.

The broken line showing of the surfboard and fin in FIG. 10 is included for the purpose of illustrating environment of the claim while all other broken lines are included for the purpose of illustrating portions of the tool with brush; the broken lines form no part of the claim.
